UNITED STATES PATENT OFFICE.

OSCAR TERHELL, OF LOS ANGELES, CALIFORNIA.

DESIGN FOR A TRAFFIC-SIGNAL CASING.

Application filed January 15, 1924. Serial No. 8,318. Term of patent 7 years.

To all whom it may concern:

Be it known that I, OSCAR TERHELL, a citizen of the United States, residing at Los Angeles, in the county of Los Angeles and State of California, have invented a new, original, and ornamental Design for Traffic-Signal Casings, of which the following is a specification, reference being had to the ac-

companying drawing, forming part thereof.

Figure 1 is a front elevation and Figure 2, is a side elevation of a traffic signal casing showing my new design.

I claim:

The ornamental design for a traffic signal casing, as shown.

OSCAR TERHELL.
